Albert E. Delmar
ATTORNEYS

Patented Oct. 20, 1925.

UNITED STATES PATENT OFFICE.

MAURICE JOSEPH STACK, OF COHOES, NEW YORK.

ROLL-WINDING DEVICE.

Application filed March 16, 1925. Serial No. 16,080.

To all whom it may concern:

Be it known that I, MAURICE J. STACK, a citizen of the United States, residing at Cohoes, in the county of Albany and State 5 of New York, have invented a new and Improved Roll-Winding Device, of which the following is a specification.

The invention has for its object to provide a particularly simple roll winder structure 10 economic to manufacture and efficiently effective in use as a means for evenly and systematically rolling continuous lengths of material, such as cotton batting adapted for use in automobile upholstering or the like, 15 into suitably proportioned rolls for shipment in accordance with the improved method of preparing such batting disclosed in my application for Patent Serial No. 16,079 filed March 16, 1925.

With the above and other objects in view 20 that will hereinafter appear the invention further resides in the novel details of construction, combination and arrangement of parts, first fully described in the following 25 detailed description, then particularly pointed out in the appended claims, reference being had to the accompanying drawing, in which:—

Figure 1 is a detail perspective view illustrating the invention in use.

Figure 2 is an end elevation of the invention.

Figure 3 is a plan view of the invention.

Figure 4 is a detail vertical section taken 35 across the double threaded feed screw at a position of the guide horn.

Figure 5 is a detail longitudinal section 40 of one of the tubes upon which the rolls are formed, the supporting shaft being shown in cooperative position therein.

In the drawings, 1 indicates the discharge 45 end of any type of machine adapted to the forming of cotton batting in continuous length for use in automobile upholstering and the like. The final pressure rolls of the machine are indicated by the numeral 2 and the guides therefor by the numeral 3. Rest rollers 4, suitably supported by the frame 50 5 may be provided to receive the continuous length of batting 6 as it leaves the presser rolls 2 and which serve as convenient supports between which a depending compensating loop of the batting may be formed at the start of the winding operation to compensate for the variations in winding surface contact during the winding of the roll

of batting. The utility of forming the loop will be well understood when it is considered that the feeding speed of the rolls 2 is constant while the amount of batting wound 60 onto the winding device per revolution of the winding rollers increases gradually as the roll wound round the receiving core from those rollers increases in diameter.

A suitable framing 7 is provided and a 65 pair of relatively large winding and supporting rollers 8 are provided, the trunnions 9 of which have bearing, as at 10, upon the top end cross bars of said framing. The trunnions at like ends of each roller 8 70 may be sprocket equipped, as at 11, and a suitable transmission chain 12 provided to cooperatively join said sprockets so that when power is applied to the driver sprocket 13, with which one of the trunnions 9 is 75 equipped, through the medium of the power chain 14, the rollers 8 will be caused to rotate in like direction and at the same speed.

A suitable roll end confining wing structure 15 is secured upon each frame end for 80 suitably abutting the ends of the roll as wound to aid in holding the same in a neat and orderly manner. Each wing 15 is centrally vertically slotted as at 16 to permit the mounting, and vertical movement during winding action, of the roll centering and supporting rod 17 adapted to receive the spacing plugs 18 and the hollow paper cores 19 upon which the batting rolls are wound.

For suitably guiding and positioning the coils of the batting while the roll is being wound, I provide a double threaded screw 90 20 the trunnions 21 of which have suitable bearings as at 22 upon the ends of the framing 7, a suitable cylindrical housing 23, 95 slotted as at 24 and securely mounted upon the bracket 25, is provided and serves to encase the said screw and to support and guide movement of the guide horn through which the said batting is threaded.

One trunnion 21 of the screw 20 is extended and provided with a sprocket 26 over which and over the sprocket 27 on the trunnion 9 of the adjacent roller end, takes the transmission chain 28, for the purpose of 105 imparting rotative motion to the said screw 20.

The guide horn above mentioned is indicated by the numeral 29 and it is carried by the sleeve 30 which slidably encircles the 110 housing 23 and is also supported by the rest block 31 which slidably engages the top

edge of the rest sill 32. The sleeve 30 is equipped with a pin 33 which projects radially inward through the longitudinal slot-way 24 into engagement with the double 5 thread of the screw 20, see Figure 4.

In operation, the batting end is threaded through the horn 29 which will be at its starting position at a proper side of the device adjacent one wing 15. The rod 17 10 with a paper core 19 surrounding it will be placed in position in the slots 16 and resting upon the rollers 8.

The end of the batting would be started around the core 19 and power applied 15 through the connections 9—14 to rotate the rollers 8. Rotation of the rollers 8 effects both the winding of the batting upon the core 19 and rotation, through connections 26—28, to the screw 20. As the winding 20 progresses the horn 29 will be fed across the length of the core 19 until the first layer is wound when the pin 33 will reach the end of the groove directed in that direction and move into the reverse direction groove 25 causing the horn to again traverse the length of the core 19 to lay the second layer of batting thereon. The alternate feeding of the horn 29 from side to side effects a neat and systematic laying of the coils of the 30 batting in even and close edge to edge relation without any possibility of uneven strains or twisting actions being imparted to the fibres of that batting.

From the foregoing description, taken in 35 connection with the accompanying drawings, it is thought the novel details of construction, manner of operation and advantages of the invention will be readily apparent to those familiar with the purposes 40 to which the same is addressed.

What I claim is:—

1. A roll winding device comprising a supporting frame, winding and supporting rollers mounted upon the framing, a winding core adapted to rest upon the winding and supporting rollers for receiving the roll being wound and to be supported and rotated by said rollers for effecting the winding of said roll, means for guiding the continuous length of material as it is wound, said guiding means including a guide horn through which the material is threaded, a double threaded screw, a cylindrical stationary longitudinally slotted housing for carrying the horn and slidably encircling the housing, a pin carried by the sleeve and projected through the slot of the housing into engagement with the double thread of the screw, whereby when the screw is rotated the horn will be caused to alternately traverse the length of the core from side to side of the framing, and means for imparting rotation to said winding and supporting rollers.

through the slot of the housing into engagement with the double thread of the screw whereby when the screw is rotated the horn 60 will be caused to alternately traverse the length of the core from side to side of the framing, and means for imparting rotation to said screw from one of the supporting and winding rollers. 65

2. A roll winding device comprising a supporting framing, winding and supporting rollers mounted upon the framing, a winding core adapted to rest upon the winding and supporting rollers for receiving the roll being wound and to be supported and rotated by said rollers for effecting the winding of said roll, vertically slotted wings for abutting the roll ends and for guiding vertical movement of the core as said roll is wound, said core comprising a hollow cylindrical core adapted to remain in the wound roll and a supporting rod suitably spaced centrally removably therein and having its ends vertically movable in the slots of the 75 wings, and means for imparting rotation to said winding and supporting rollers.

3. A roll winding device comprising a supporting framing, winding and supporting rollers mounted upon the framing, a winding core adapted to rest upon the winding and supporting rollers for receiving the roll being wound and to be supported and rotated by said rollers for effecting the winding of said roll, vertically slotted wings 90 for abutting the roll ends and for guiding vertical movement of the core as said roll is wound, said core comprising a hollow cylindrical core adapted to remain in the wound roll, a supporting rod suitably spaced centrally removably therein and having its ends 95 vertically movable in the slots of the wings, and means for imparting rotation to said winding and supporting rollers.

4. A roll winding device comprising a supporting framing, winding and supporting rollers mounted upon the framing, a winding core adapted to rest upon the winding and supporting rollers for receiving the roll being wound and to be supported and rotated by said rollers for effecting the winding of said roll, vertically slotted wings 100 for abutting the roll ends and for guiding vertical movement of the core as said roll is wound, said core comprising a hollow cylindrical core adapted to remain in the wound roll, a supporting rod suitably spaced centrally removably therein and having its ends 105 vertically movable in the slots of the wings, means for guiding the continuous length of material as it is wound, said guiding means including a guide horn through which the material is threaded, a double threaded screw, a cylindrical stationary longitudinally slotted housing for carrying the horn and slidably encircling the housing, a pin carried by the sleeve and projected through the slot of the housing into engagement with the double thread of the screw, whereby when the screw is rotated the horn will be caused to alternately 110 traverse the length of the core from side to side of the framing, and means for imparting rotation to said winding and supporting rollers.

MAURICE JOSEPH STACK.
